UNITED STATES PATENT OFFICE.

EDWIN S. PRIDHAM AND PETER L. JENSEN, OF NAPA, CALIFORNIA, ASSIGNORS TO COMMERCIAL WIRELESS & DEVELOPMENT CO., OF SAN FRANCISCO, CALIFORNIA, A CORPORATION OF ARIZONA.

AMPLIFYING-RECEIVER.

1,266,988.

Specification of Letters Patent. Patented May 21, 1918.

Application filed July 3, 1916. Serial No. 107,443.

To all whom it may concern:

Be it known that we, EDWIN S. PRIDHAM and PETER L. JENSEN, both citizens of the United States, residing at Napa, in the county of Napa and State of California, have invented new and useful Improvement in Amplifying-receivers, of which the following is a specification.

This invention relates to amplifying receivers of the type shown and described in our Patent, No. 1,051,113, dated January 21, 1913, for use in telephony, and has for its object to simplify and improve the construction and operation of such devices.

In amplifying receivers of this type, a conducting coil for telephonic currents, is disposed in a magnetic field so as to cut transversely the lines of force of the field, whereby a force acts upon the coil, to vibrate the same at right angles to the magnetic force, the magnitude of the vibrating force being the product of three factors, namely, the length of the conductor perpendicular to the lines of force of the magnet, the strength of the magnetic field, and the strength of the current flowing through the conducting coil. By making the magnetic force great and disposing a great length of the conductor to the influence of the magnet, vibrations of the coil may be produced to actuate a diaphragm for reproducing sound waves of considerable amplitude, even where the strength of the telephonic currents is comparatively weak.

It is therefore important, in order to produce an intense magnetic field, to have a very narrow air gap between the pole pieces of the magnet and also the greatest possible length of conductor exposed in the magnetic field and at the same time restrict the size and weight of the coil without impairing its rigidity. The form of coil herein provided, will present a maximum length of wire to the magnetic force, is light, thin and affords the desired rigidity for imparting all its vibratory movements to the diaphragm to which it is attached. Other novel and advantageous features of the present device will become apparent upon a further understanding of the invention.

One form which our invention may as-

sume is exemplified in the following description and illustrated in the accompanying drawings in which—

Figure 1 shows a side elevation of the device embodying our invention, certain parts being broken away to show the interior construction.

Fig. 2 shows a plan view of the bottom of the same.

Fig. 3 shows a perspective view of the novel form of conducting coil employed in our device.

Fig. 4 shows a similar view, disclosing a slight modification.

Fig. 5 shows a cross sectional view of the coil.

Fig. 6 shows a diagram of the electrical connections employed in the device.

Fig. 7 shows a side elevation of a portion of the device, with the casing in section.

Fig. 8 shows a plan view of the magnetic pole pieces with the sound box and vibrating coil in position thereon.

Fig. 9 shows a plan view of the inner side of the sound box and diaphragm with the vibrating coil attached thereto, and

Fig. 10 shows a sectional view on line 10—10, Fig. 7.

In the drawings, a receiver is shown as comprising a casing 10, within which is an electro-magnet 11, preferably of the horseshoe type and having pole pieces 12 directed toward each other and separated by a narrow air gap. Within this gap is our improved coil 13, consisting generally of a large number of turns of fine wire approximating an annular form, said wires being bunched at the back 14 and flattened or spread out at the front 15, thereby presenting a coil wedge-shaped in cross section, as shown in Fig. 5. The bundle of wires at the back side of the coil is secured together by means of tie wires 16. Mica or other non-conducting plates 17 are placed at opposite sides of the coil and are preferably made smaller than the coil and arranged so that the bundle of wires at the back is exposed, projections 18 on the corners of the plates being provided to engage the sides of the bunched wires. A bracket-shaped clip 19 of light material, such as aluminum, is rigidly

secured to each plate 17 at the back side thereof, one of said clips being held by a rivet or screw 21 passing through the central portion of both plates, and the other clip 5 being held by means of screws or rivets 21 one at either side of the central portion of the plates, said last mentioned clip being bifurcated at its inner end for this purpose. The clips 19 have flanges 22 at their outer 10 ends, adapted to be rigidly secured to a receiver diaphragm 23 by means of screws or fasteners 24. The diaphragm 23 is stretched between plates 25 secured to the casing 10 and forming a sound box. Preferably a screw-threaded nozzle 26 is provided for the sound box to receive an ear-piece or amplifier not shown.

The metallic connections between the coil 13 and the transmission line are such as to 15 prevent interference with the free vibration of the diaphragm and coil and to obviate any danger of the connection becoming broken on account of the necessary vibrations which take place. One end of the coil 20 is connected to one of the posts 21 and the opposite end of the coil is connected to the post 20. Thin metallic strips 27 are glued 25 to the diaphragm with shellac or other suitable substance and insulating material 28 in addition to the shellac may be laid between 30 the metallic strips and the diaphragm. The said strips 27 are secured at their inner ends to the fasteners 24 on the diaphragm and extend radially outward to the periphery of 35 the diaphragm where they are projected downwardly and attached to binding posts 29 secured to an insulating block 30 on the sound box. The brackets or clips 19 in the form shown in Fig. 3, may serve as conductors 40 between the metallic strips 27 and the coil, or separate wire connections 31 may be made between these parts, as shown in Fig. 4, in which case the bifurcation on the end of one of the brackets may be dispensed with 45 and both brackets made identical and secured in place by the centrally positioned screw 20.

An operating circuit for the receiver is shown in Fig. 6, as an illustration of one manner of operating the device. This circuit includes service mains 32 and 33, to 50 which the winding 34 on the magnet is connected, and also a storage battery 35 connected to said mains. A multi-contact controlling switch 36 is shown as located between the magnetic winding and the storage 55 battery. Transmitters 37 are shown as connected to the storage battery 35 and to the primary induction coil 38, a return connection being had through the switch 36. The 60 secondary of the induction coil is connected to the vibrating coil 18.

The construction and arrangement of the coil 18 go to make up a thin, rigid member with a maximum presentation of the conducting wire. As will be noted, the wire is 65

spread out at the front portion of the coil, where it intersects the magnetic field, thereby exposing practically all of the turns of the wire to the influence of the magnet. The back portion of the coil, by having its wires 70 bunched, forms a support for the entire coil, affording the desired rigidity. The clips 19 obviously afford a strong and rigid connection between the coil and diaphragm.

By securing the thin, metallic conducting 75 strips to the diaphragm, we overcome the difficulty presented in attaching a conductor to a vibratory member. The movement of the diaphragm at or near its periphery is obviously slight and therefore by fastening 80 the conducting strips to the diaphragm at this point, there will be a minimum of bending action on the strips, with a consequent lessening of the danger of breakage.

Various changes in the construction and 85 arrangement of the several parts herein shown and described, may obviously be employed, without departing from the spirit of our invention, as disclosed in the appended 90 claims.

Having thus described our invention, what we claim and desire to secure by Letters Patent is—

1. In an amplifying receiver for telephony, a magnet having a narrow air-gap and 95 a transversely movable coil disposed in said air-gap and carrying telephonic currents and comprising a large number of annular turns of wire spread over a large area and forming a wide flat surface of such thinness 100 as to require an external support.

2. In an amplifying receiver for telephony, a magnet having a horse-shoe core with its pole pieces extending inwardly and spaced a slight distance apart and a transversely movable coil for the telephonic currents disposed between said pole pieces and comprising a large number of annular turns of wire spread over a large area and forming a wide flat surface, said coil connected 110 to the diaphragm of the receiver, and connections between the coil and the operating circuit comprising thin metallic strips.

3. In an amplifying receiver for telephony, a magnetic field and a conducting coil 115 for telephonic currents disposed therein and rigidly attached to the diaphragm of the receiver, said coil comprising a large number of annular turns of fine wire having the portion disposed in the field spread over a 120 flat surface and the opposite portion bunched to form a support for the coil.

4. In an amplifying receiver for telephony, a magnetic field and a conducting coil for telephonic currents disposed therein and 125 rigidly attached to the diaphragm of the receiver, said coil comprising a large number of annular turns of fine wire having the portion disposed in the field spread over a flat surface and the opposite portion 130

bunched to form a support for the coil, insulating plates on the opposite sides of said coil, secured together, and binding posts on said plates to receive the ends of the coil.

5. 5. In an amplifying receiver for telephony, a magnetic field, a conducting coil for the telephonic currents disposed in said field and comprising a number of annular turns of fine wire having the portion disposed in the field spread over a wide flat surface and the opposite portion bunched to form a support for the coil, and bracket-shaped clips for attaching said coil rigidly to the diaphragm of the receiver.
10. 6. In an amplifying receiver for telephony, a magnetic field, a conducting coil for the telephonic currents disposed in said field and comprising a number of annular turns of fine wire having the portion disposed in the field spread over a wide flat surface and the opposite portion bunched to form a support for the coil, bracket-shaped clips for attaching said coil rigidly to the diaphragm of the receiver and connections between the 25 ends of said coil and the clips.

7. A conducting coil comprising a large number of annular turns of fine wire with the portion at one side spread over a wide flat surface and the portion at the opposite side bunched to form a rigid support for the coil, insulating plates secured to

opposite sides of the coil and brackets secured to the plates for mounting the coil.

8. In a receiver for telephony the combination with a sound box and its diaphragm, of a magnetic field, a vibrating conducting coil for the telephonic currents disposed in said field, and rigidly secured to the diaphragm and connections between said coil and the operating circuit comprising thin 40 metallic strips secured to the diaphragm.

9. In an amplifying receiver for telephony, the combination with a sound box and its diaphragm, of a magnetic field, a vibrating coil disposed in said field, rigid fastening 45 means for connecting said coil to the diaphragm, means for connecting said coil with an operating circuit, comprising thin metallic strips secured at their inner ends to the diaphragm by said coil fastening 50 means and extending outwardly along the surface of the diaphragm to a point near the periphery thereof, and stationary means for receiving the outer ends of said strips.

In testimony whereof we have hereunto 55 set our hands in the presence of two subscribing witnesses.
